UNITED STATES PATENT OFFICE.

VIRGIL E. METCALFE, OF DELICIAS, ORIENTE, CUBA.

CENTRIFUGAL SEPARATOR.

Application filed August 16, 1923, Serial No. 657,739. Renewed April 6, 1927.

This invention relates to centrifugal separators and more particularly to centrifugal separators having an outer rotating perforated basket and an inner rotating conveyor.

5 The main object of the invention is to provide a centrifugal separator having the above mentioned main elements and means for conveniently controlling the speeds of these elements.

10 A further object of the invention is to so arrange the rotating basket and conveyor as to materially reduce the power necessary to rotate the elements relatively to each other.

15 With these and other objects in view, as will hereinafter appear, the invention consists in the novel construction and arrangement of parts including a novel transmission mechanism constituting the apparatus, all as will be more fully hereinafter disclosed 20 and particularly pointed out in the claims.

For a complete understanding of the invention reference is to be had to the following description and the accompanying drawings in which:

25 Fig. 1 is a vertical sectional view of the apparatus;

Fig. 2 is a top plan view;

Fig. 3 is a cross section on the line 3—3 of Fig. 1;

30 Fig. 4 is a cross section of Fig. 1 on the line 4—4;

Fig. 5 is a diagram of the electrical transmission; and

35 Fig. 6 is a fragmentary side elevation of two perforated baskets joined together.

40 Referring to the drawings in detail, the reference character 1 designates a perforated basket to which is joined another basket 1^a, each basket being of the shape, by preference, of a truncated cone. Interior of each basket, concentric therewith and adequately spaced therefrom, is a conveyor which is preferably of the Archimedes screw type, said conveyors being represented by the numerals 2 and 2^a. It will be understood that in the process of separating liquid material from the solid particles, centrifugal force exerted by the basket which is caused to rotate as will presently appear will expel the liquid through the perforations of the basket while the solid particles will be retained therein between it and the outer surface of the conveyor which by rotating at the proper speed with respect to the basket will cause 50 the solid particles to be forced longitudinal-

ly of the basket to the open end thereof where the solid particles will be caught in a suitable receptacle.

In order to obtain accurate rotative speed relation between the basket and the conveyor, there is provided a novel electric transmission which will be presently described. There is arranged a fixed shaft 3 secured to a suitable pedestal or standard 4, and secured to this shaft 3 is the stator A of a phase wound induction motor. Journalled on the shaft 3 and having roller bearing connection therewith, as clearly shown by Fig. 1 of the drawings, is a rotor B having a phase winding mounted in its inner surface, and this winding is connected to a similar winding positioned in slots in the outer surface of the rotor B, the latter winding being designated by the reference character B'. Rotatively mounted on the rotor B is a rotor C on the inner surface of which is placed a short circuited winding. It will be readily apparent that the stator A and rotor B constitute a phase wound induction motor, while the rotor B, considering the winding B' only, and the rotor C constitute a squirrel cage induction motor. Thus, there are provided two induction motors wherein the inner winding on the rotor B is the secondary member with respect to the primary member A, and the winding B' is a primary member with respect to the rotor C which is a secondary member. The terminals of the stator winding A may pass through the axial bore 3* in the end of the shaft 3. Reference is here made to Fig. 5 of the drawings for a clear understanding of the electrical transmission. To control the voltage impressed on the stator A for a purpose to be presently explained more in detail there is provided a three phase induction voltage regulator R.

When the winding on the stator A is excited from a suitable power circuit, a current is generated in the inner winding of the element B, causing it to revolve, and this current also excites the outer winding B' which in turn induces the flow of current in the element C. The speed of element B will increase to some value below synchronism depending upon the slip, and if the element C is connected to run in the same direction as B, its speed will be greater than that of B depending upon the slip between A and B, assuming constant load and voltage. If for any reason, there is a change in slip of B

with respect to A, there will be a change in the relative speeds of B and C, and comparatively small changes in slip between A and B will cause comparatively large changes in the relative speeds of B and C. Now, the slip in an induction motor under constant load becomes greater with a decrease in the impressed voltage and less with an increase of voltage. Taking advantage of this principle, it is proposed to control the relative speeds of B and C by varying the voltage on the stator A by means of the induction voltage regulator R. It is thus apparent that a very convenient means of controlling the relative speeds of the basket and the conveyor may be employed by connecting the basket to one and the conveyor to the other of the elements B and C.

Accordingly, the conveyor 2^a is connected to the element C at the projection 5 of the hub 6 by which the rotor C is mounted on the hub 7 of the rotor B, as is obvious from an inspection of Fig. 1; and the basket 1^a is connected so as to be rotated by the rotor B by means of the spider arms 8 which are secured to the hub 9 by means of bolts 10. It will be understood that the basket 1 rotates with the basket 1^a by reason of the fact that they are joined at their adjacent ends or are integral with each other, as may be desired. The conveyor 2 is likewise rotated by the conveyor 2^a, as may be seen more clearly from Fig. 1, the two conveyors being joined together at their contiguous ends. A ball bearing 11 is provided between the baskets 1, 1^a and the conveyors 2, 2^a. At the top of conveyor 2^a, is a disk 12 spaced from a disk 13 at the bottom of the conveyor 2 by the studs 12^a, the upper disk 13 having an opening 14 provided with the upstanding deflecting rim 14^a whereby the material received from the spout 15 is divided, part passing to the upper basket 1 and the rest passing to the lower basket 1^a. The conveyors 2 and 2^a are provided with openings through which the material may flow to the baskets.

The liquid material that is expelled through the baskets or screens 1 and 1^a will be caught in the receiver 16, having the opening 17 through which the liquid may be removed, and the solid particles will be expelled at the ends of the baskets and will be caught in the receptacles 18 and 19 at the upper and lower ends of the apparatus. The receptacles 18 and 19 may preferably be made in two parts so that each receptacle may be removed, at will. In Fig. 4, the receiver 19 is shown in two parts, and it will be understood that the receiver 18 may be likewise constructed and arranged. Any suitable supports for the receivers 18 and 19 may be provided, but the upper receptacle is supported, for example, on the arms 20 spaced circumferentially of the receiver

16, and the lower receptacle is supported on the arms 21 radiating from the base or standard 4.

When it is desired to wash the solid particles before being discharged, water connections 22 and 22^a may be employed, baffles 23 and 23^a being arranged to prevent the water from coming in contact with the material near the top and bottom of the upper and lower baskets respectively. It will be obvious that steam connection may be made with the cylinder receiver 16 so that steam may be admitted between the whirling basket and the receiver for periodically cleaning the basket when necessary or desirable.

The apparatus has been described in detail and its operation is believed to be clearly understood. While the centrifugal separator is capable of use generally, it is especially advantageous for drying sugar and separating the molasses from the sugar. A continuous stream of massecuite may be admitted through the spout 15. The stream will divide, and pass to the upper and lower baskets while in motion, the molasses being expelled through the apertures of the baskets and the sugar being discharged at the ends of the baskets into the receptacles provided therefor. The apparatus may similarly be used for drying salt, as is obvious.

As previously stated, the means for rotating the baskets and the conveyors affords a convenient means for controlling the relative speeds of the latter elements, and in order to obtain a sugar of desired and uniform quality proper speed control of the main elements is very advantageous, if not necessary. As pointed out above, any small change in the slip between the stator A and the rotor B will be reflected in a comparatively large change in the relative speeds of the rotor B and the rotor C and consequently between the speeds of the baskets and the conveyors. Therefore, for fine adjustments a small change in the impressed voltage will give the desired change in the speed of the conveyor with respect to the basket. For example, with the machine in operation, if the sugar discharged contains too much molasses and it is desired to obtain a dryer sugar, the relative speeds of the basket and the conveyor may be adjusted by varying the voltage on the stator to cause the sugar to remain in the basket for a longer period to enable a longer period of action of the centrifugal force of the rotating basket to expel the molasses. It is thus apparent that a very fine adjustment may be made, thus making it possible to produce different grades of sugar of uniform quality.

From the above description, it will be apparent that it is not essential to my invention that more than one basket and conveyor be provided, but in order to offset the end

thrust of the rotating screw, the two baskets and conveyors are arranged as shown so that the end thrust of one conveyor neutralizes the end thrust of the other conveyor.

- 5 It has already been noted that by mounting the motor for actuating the conveyor upon the motor that actuates the basket, only sufficient power to operate the conveyor at the difference in speeds is necessary as distinguished from the power necessary to operate the conveyor if its operating motor were not mounted on the basket operating motor. It is also important to note that if the conveyor is made to operate in a direction opposite to that of the basket, the falling mass will in frictional contact with the disks 12 and 13 will exert a retarding action on the conveyor in such a direction as to aid the conveyor operating motor.
- 10 The foregoing disclosure contains a more or less general description and illustration of the preferred embodiment of the invention, but the mechanical details and expediencies may be supplied to suit different conditions that may arise. In view of the disclosure, certain changes in the construction and arrangement of parts may be made, but since the description and drawings are to be considered illustrative only of the invention, it is to be understood that this invention contemplates all such changes as come within the scope of the appended claims.

15 Having thus described my invention, what I claim and desire to secure by Letters Patent of the United States is:

1. In a centrifugal separator, a rotatable annular screen, an inner rotatable conveyor coaxial with said screen, and means for varying the speed ratio of said rotatable screen and conveyor comprising electro-inductive means for operating said screen and conveyor.
2. In a centrifugal separator, a rotatable annular screen, an inner rotatable conveyor, an induction motor for operating one of said elements, and an induction motor for operating the other of said elements, the rotor of one of said induction motors comprising the stator of the other of said induction motors.
3. In a centrifugal separator, a rotatable annular screen, an inner rotatable conveyor, an induction motor for operating one of said elements comprising an internal stator and an external rotor, and an induction motor for operating the other of said elements comprising the rotor of said first mentioned in-

duction motor and a rotor in electro-inductive relation therewith.

4. The combination of a centrifugal separator having an outer rotating element and an inner rotating element, means for rotating said elements with respect to each other comprising an induction motor for each element, one element of one motor being in inductive relation with an element of the other motor whereby variations in slip of one motor cause variations in the speed ratio of the two motors, and means for varying the slip of one of the motors.

5. In a centrifugal separator, an outer rotating element and an inner rotating element, a fixed shaft, an induction motor stator secured to said shaft, a rotor for said induction motor surrounding said stator for operating one of said elements, and a rotor in inductive relation with said first mentioned rotor for operating the other of said elements at a speed proportional to the speed of the first mentioned element.

6. In a centrifugal separator, a rotatable annular screen, a rotatable conveyor, a fixed shaft coaxial with said conveyor and screen and arranged within said conveyor, an induction motor stator secured to said shaft, a rotor rotatably mounted on said shaft for rotating one of said rotatable elements, and another rotor inductively related to said first rotor and rotatably mounted thereon for operating the other of said rotatable elements.

7. The combination of two rotatable members and means for rotating said members at different speeds comprising two induction motors, the primary winding of one motor being connected to the secondary winding of the other motor, and means for varying the impressed voltage on one of said motors, to thereby vary the slip of said motor and thereby vary the speed ratio of the two motors.

8. The combination of a centrifugal separator having two rotatable members and means for rotating said members at different speeds comprising two induction motors, the primary of one motor being connected to the secondary of the other motor, whereby variations in slip of one motor causes variations in the speed ratio of the two motors, and means for varying the slip of one of said motors.

In witness whereof, I hereunto affix my signature.

VIRGIL E. METCALFE.
